UNITED STATES PATENT OFFICE.

VALENTINE W. MILLER, OF FONDA, IOWA.

AERIAL MAIL-CARRIER.

1,242,835.

Specification of Letters Patent.

Patented Oct. 9, 1917.

Application filed June 11, 1917. Serial No. 173,948.

To all whom it may concern:

Be it known that I, VALENTINE W. MILLER, a citizen of the United States of America, and resident of Fonda, Pocahontas county, 5 Iowa, have invented a new and useful Aerial Mail-Carrier, of which the following is a specification.

The object of this invention is to provide improved means for carrying and conveying 10 objects such as mail matter through the air.

A further object of this invention is to provide means adapted to be suspended from a track and further adapted to be self propelled from either end to the other of said track.

A further object of this invention is to provide improved means independent of each other for driving an aerial carriage 20 from either end to the other of a track.

A further object of this invention is to combine with an aerial carriage provided with means for self-propulsion in opposite directions, a receptacle adapted to contain 25 objects such as mail matter.

My invention consists in the construction, arrangement and combination of elements hereinafter set forth, pointed out in my claims and illustrated by the accompanying 30 drawing, in which—

Figure 1 is a side elevation, partly in section, illustrating my improved device. Fig. 2 is an end elevation, partly in section, of the same device and showing in addition thereto 35 a portion of an aerial track from which the device is suspended.

In the construction of the device as shown the numeral 10 designates generally a housing or box which may be provided with any 40 suitable doorway or detachable members through which access may be had to the interior thereof for substitution or repair of parts. The housing or box 10 preferably is weather-proof as it is designed to be employed outside and subject to all manner of 45 climatic conditions and changes. Supporting shafts 11, 12 are pivoted in a common horizontal plane in the sides of and extend across the housing or box 10, and grooved 50 supporting wheels, 13, 14 are mounted on said shafts and are connected thereto by ratchet devices 15 arranged oppositely so that in the travel of said wheels in either direction one of the wheels will be driven by 55 its shaft and the other wheel will revolve

freely on its shaft. The grooved supporting wheels 13, 14 preferably are lined in their grooves with friction or brake-shoe material.

The housing or box 10 is formed with a 60 longitudinal notch in each end and a corresponding slot in one side, indicated by the numeral 16, extending across the vertical plane occupied by the wheels 13, 14 to admit an aerial track 17 carried by arms, one of 65 which is shown in Fig. 2 and indicated by the numeral 18, said arms being suitably supported and carrying the aerial track in substantially taut condition. The wheels 13, 14 travel on the track 17 and support the 70 housing and other elements therein or suspended therefrom. Independent trains of gearing 19, 20 extend from the shafts 11, 12 respectively to spring-boxes 21, 22 carried on winding shafts 23, 24 extending across 75 and journaled at their ends in the sides of the housing, said winding shafts also being in a common horizontal plane. Oppositely arranged ratchet devices 25, 26 connect the spring-boxes 21, 22 to the winding shafts 80 23, 24. The spring-boxes carry the initial gears of the independent trains 19, 20, and said trains preferably are speed-increasing from the spring-boxes to the supporting shafts. The winding shafts may be turned 85 in any desired manner, as by a detachable key (not shown) for the purpose of winding springs in the boxes, one of said springs being shown in Fig. 1 and indicated by the numeral 27. The springs are oppositely arranged in the boxes.

A latch 28 is pivoted at one end to the center of the top of the housing 10 and is adapted to be moved through an arc from one end to the other and project over and beyond 95 either end of the housing. The latch 28 is provided with an offset or lug 29 extending downwardly at its outer end and an inclined terminal member 30, said inclined terminal member being adapted to engage and carry 100 the lug over a stop 31 suitably located at either end of the track 17, said latch yielding upwardly as the lug rides over the stop. It is the function of the latch and stop to hold the aerial carriage at either end of the 105 track until the same is manually released and also to provide a cushioned stopping device for the aerial truck on its approach to either end of the track.

A receptacle 32 of any suitable form is 110

fixed to and suspended beneath the housing or box 10 and is adapted to receive objects to be conveyed, such as mail matter.

Suitable detent devices 33, 34 are mounted in and partly extend through the ends of the housing or box 10 and are adapted to engage at times one wheel of each independent train of gearing and hold the same against the tension of the driving springs.

Assuming the use of this device in carrying mail between a patron's home and a mail carrier's station, such as on a rural free delivery route, one end of the track 17 would be contiguous to the home and the other end thereof contiguous to the station and each end of the track would be provided with a stop 31. The patron winds both springs and mounts the housing on the track in the manner described, turning the latch 28 toward the station terminal. Then the patron releases the outgoing train of gearing by withdrawing the detent device nearest the home, such as 34, and permits the carriage to be moved forward toward the station because of traction of the rearmost grooved supporting wheel, such as 14, on the track 17, said wheel being driven in the proper direction to advance the carriage by the corresponding spring 27 acting through the train 20. To return the carriage from the station to the home the mail carrier, having deposited the mail if any in the receptacle 32, reverses the position of the latch 28 and releases the other train of gearing by withdrawal of the detent devices 33 from engagement therewith. This done the carriage advances because of traction of the supporting wheel 13 on the track 17, said supporting wheel being driven by the other spring through the train 19.

I do not desire to be understood as limiting myself to the details of construction shown and described as the same may be modified in many particulars without departing from the spirit of my invention.

I claim as my invention—

1. An aerial carrier, comprising a housing formed with a laterally opening slot adapted to admit a track along which said carrier

travels, alining supporting wheels adapted to engage said track, means for pivotally mounting said wheels in said housing, oppositely driven spring actuated independent trains of gearing acting on said pivoting means, independent manually released detent devices engaging said trains of gearing, and a container suspended from said housing.

2. An aerial carrier, comprising a housing formed with a laterally opening slot adapted to admit a track along which said carrier travels, alining supporting wheels adapted to engage said track, means for pivotally mounting said wheels in said housing, oppositely driven spring actuated independent trains of gearing acting on said pivoting means, independent manually released detent devices engaging said trains of gearing, a latch reversibly mounted on said housing and adapted to engage independent stops selectively, and a container carried by said housing.

3. An aerial carrier, comprising a housing formed with a laterally opening slot adapted to admit a track along which said carrier travels, alining supporting wheels adapted to engage said track, means for pivotally mounting said wheels in said housing, said pivoting means including oppositely arranged ratchet devices whereby one of said wheels remains idle in movement of said housing in either direction, oppositely driven spring actuated independent trains of gearing acting on said pivoting means, independent manually released detent devices engaging said trains of gearing, and a container carried by said housing.

4. An aerial carrier adapted for travel on a track, comprising a housing and means for straddling said track by said housing, means for supporting said housing for travel on said track, independently operated means for driving said housing selectively in opposite directions on said track, said means for driving including independent spring motors, and a container suspended from said housing.

VALENTINE W. MILLER.
